EXHAUST DEFLECTOR

Linus E. Russell, Springfield, Ohio, assignor to Peters & Russell, Inc., Springfield, Ohio, a corporation of Ohio

Application January 22, 1959, Serial No. 54,272

Term of patent 14 years

(Cl. D14—6)

Fig. 1 is a perspective view of an exhaust deflector embodying my design;

Fig. 2 is a side view thereof;

Fig. 3 is a front view thereof; and

Fig. 4 is a bottom view thereof.

I claim:

The ornamental design for an exhaust deflector, substantially as shown.
